Inventor,
Samuel B. Freethy,
By his Attorney, R. J. Lander.

UNITED STATES PATENT OFFICE.

SAMUEL B. FREETHY, OF SURRY, MAINE.

COMBINED TOOL.

SPECIFICATION forming part of Letters Patent No. 393,227, dated November 20, 1888.

Application filed February 29, 1888. Serial No. 265,716. (No model.)

To all whom it may concern:

Be it known that I, SAMUEL B. FREETHY, a citizen of the United States, residing at Surry in the county of Hancock and State of Maine, have invented a new and useful Combined Tool; and I do hereby declare that the following is a full, clear, and exact description of the invention, which will enable others skilled in the art to which it appertains to make and use the same.

My invention relates to a combined tool for household use; and it consists of the combination of several new and useful tools into one instrument so constructed and arranged that the individuality of each tool is reserved for its separate purpose, or they may be taken collectively and a new benefit obtained by their combination.

The object of my invention is to provide a new instrument for varied mechanical purposes that will take the place and save the expense of separate artisan tools for ordinary household use.

In the drawing the figure is a perspective view of my combined tool, showing the handle and jaws partly open.

Similar letters of reference refer to like parts throughout the different parts of the drawing.

My invention is intended to be manufactured from iron cast to shape with its several parts attached; but it can be made from any desired metal having sufficient stiffness and strength.

As will be seen by the drawing, the invention consists of two parts united by a rivet in a manner similar to a pair of pinchers. To designate the two parts, I will call one A and the other B.

The part A is composed of the handle b, having a mortise at x, through which the part B passes. At this mortise the handle is made about three-fourths or seven-eighths of an inch wide and rounded on its upper side and concaved underneath, as shown at c. The handle b commences to taper from the mortise toward its end, which contains a boss, h, through which a square hole is made. The boss h is made large enough to allow the hole j to be made of a sufficient size to fit the projecting end of a cook-stove grate, and for this purpose it makes a handy shaker.

Across the end of the handle b, outside of the boss h, is a cross-piece, G, having its center

of sufficient thickness to allow a large slot or wrench-like opening, o, to be cut through the bar at a sufficient depth to make a good wrench at this point. The cross-piece G is tapered or reduced in size from the opening o toward each end and forms a tack-hammer at each extremity of different sizes. The sides of the smaller hammer, t, are made square, to facilitate the using of the same close up into corners, and are found very convenient in putting down carpets.

Projecting from opposite sides of the part A, at the point marked x and parallel with each other, are the two somewhat triangular-shaped pieces E' and F', projecting downward about one-half of an inch from the handle. These projections will be hereinafter more fully explained.

The part A from the mortise or point x is gradually reduced in size and bent downward, then upward in the form of a reverse curve until the end k is about parallel with the line of the handle b. The end k is now flattened and tapered to a feather-edge. A V-shaped opening, e, with its edges chamfered, is cut in this end, making a first-class tack-puller.

The second part, B, of my combined tool consists of the handle d, shank g, and jaw f. United to the shank g, near where it passes through the mortise in the part A, are the two projections E and F, similar to the projections E' and F', extending from the part A. These projections are so situated with regard to each other that their inner edges meet, or very nearly so, when the jaws of the tool are together. The inner edges of the projections F and F' are made irregular, similar to saw-teeth, and this side is used as a nut-cracker. A nut placed between the two projections F and F' is easily broken by compressing the handles of the instrument. The projections E and E' on the opposite side of the tool are used for a saw-set and are made as follows: The inner edge of the part E is hollowed or filed away each side of the place marked i, leaving a rounded ridge, i, protruding. A corresponding hollow, l, is filed out of the meeting edge of the part E' and a slight hollow, r, filed near its end. The set is now used by inserting a saw between the edges of the projections E, E', F, and F' as far as the hollow l. By compressing the handle of the tool the ridge i will press upon the top of the saw-tooth and bend it to the right set

into the hollow *l*. The parts *F* and *F'* help support and hold the saw during the process.

From the projections *E* and *F* on the part *B* the tool is gradually reduced in width, forming a shank, *g*, which contains the enlargement *f* at its end that forms the jaw of this part. The jaw *f* is made quite flat and has its corners and upper surface rounded. The metal is cut away from the under surface of this jaw, leaving a horseshoe-like ridge around its edge, into which the lower jaw, *k*, passes when the two parts are brought together. A small projection, *n*, extends internally from the center of the ridge in the upper jaw, *f*, and is so situated as to project through the V-shaped opening *e* in the lower jaw, *k*.

From the projections *E* and *F* the part *B* is shouldered to allow the handle *d* to pass through the mortise in the part *A* at this place.

20 The handle *d* is made straight, round, and slightly tapering toward the end, and its surface contains longitudinal striations, which adapt this part of my device to be used as a knife-sharpener.

25 The jaws *f* and *k*, together with the side projections, *E*, *E'*, *F*, and *F'*, are used for holding a chain dish-cloth in washing out kettles, &c., in the following manner: One of the rings of the cloth is placed upon the jaw *f* over the projection *n*.

30 The lower jaw, *k*, is then closed over this link, firmly holding it. The cloth is then brought back over the side projections, *E* *E'* *F'*

F, and a link inserted between each projection. In this position the cloth is somewhat spread out and can be used to a much better 35 advantage in various ways.

The instrument is further used in laying carpets by inserting between the jaws *k* and *f* the edge of the carpet and pressing it up against the wall. The jaw *f*, being made quite broad and 40 having its edges rounded, will not in any way tear or injure the carpet in stretching, and it can be used to a great advantage in close corners and places where to use the hands would otherwise seem impossible.

Having now described my invention, what I claim, and desire to secure by Letters Patent, is—

A combined tool consisting of the two parts *A* and *B*, united by a rivet and containing the 50 parallel projections *E*, *E'*, *F*, and *F'*, for the purpose described, the shanks *e* *g*, with their jaws *k* and *f*, constructed as shown, the handle *d*, rounded and containing longitudinal striations, and the handle *b*, provided with the boss 55 *h* and its square opening *j*, the cross-piece *G*, having hammers *m* *t* at its opposite ends, and the wrench *o*, substantially as shown and described.

SAMUEL B. FREETHY.
